UNITED STATES PATENT OFFICE.

JOHN F. HOENNINGER, JR., OF LANCASTER, PENNSYLVANIA.

BAKER'S-OVEN LIGHT.

1,296,804.

Specification of Letters Patent. Patented Mar. 11, 1919.

Application filed September 23, 1918. Serial No. 255,333.

To all whom it may concern:

Be it known that I, JOHN F. HOENNINGER, Jr., a citizen of the United States, residing at Lancaster, in the county of Lancaster, State of Pennsylvania, have invented certain new and useful Improvements in Bakers'-Oven Lights; and I do hereby declare the following to be a full, clear, and exact description of the invention, such as will 10 enable others skilled in the art to which it appertains to make and use the same.

The invention relates to a bake oven illuminating attachment, and more particularly to the class of automatically operated oven 15 illuminators.

The primary object of the invention is, the provision of an attachment or illuminator of this character, wherein on the opening of the door to the oven, a switch or valve 20 will be automatically operated thereby controlling the illuminator for the light of the oven, the door when closed being designed to shut off the light within the oven.

Another object of the invention is, the provision of an attachment or illuminator of this character, wherein the switch or valve controlling mechanism thereof is of novel form to positively control the lighting of the oven and the extinguishing of the 30 light on the opening and closing of the door.

A further object of the invention is, the provision of an attachment or illuminator of this character, which is simple in construction, readily and easily attached to the oven door frame, thoroughly reliable and efficacious in its operation, and inexpensive to manufacture and install.

With these and other objects in view, the 40 invention consists in the features of construction, combination and arrangement of parts as will be hereinafter fully described, illustrated in the accompanying drawing and pointed out in the claims hereunto appended.

In the accompanying drawing:

Figure 1, is a fragmentary front elevation of an oven and its door showing the illuminator constructed in accordance with 50 the invention applied thereto.

Fig. 2, is a sectional view transversely through the switch box showing the weight of the door pintle in engaging position when

the door is opened for the lighting of the oven.

Fig. 3, is a vertical sectional view showing a modified form of the invention.

Similar reference characters indicate corresponding parts throughout the several views in the drawing.

Referring to the drawing in detail, A, designates a portion of the front wall of a bake oven or any chamber, the interior of which it is desired to illuminate, B, the door frame and C, the vertically swinging oven door which is supported on horizontal pintles 10 which are journaled in the door frame B, as usual. At one side of the door frame, is a recess or cavity 11 in which works the weighted arm 12 which is fixed to one of the 65 pintles 10 of the door C so as to hold the same in open position on initially swinging the same from closed to open position. This arm 12, is manually operated for the opening and closing of said door as is usual. 70 Suitably mounted in the wall A and receiving an electric light bulb is a lamp socket 13 which is arranged within an electric circuit 14 having connection with the main circuit wires 15, in any suitable manner. 75

Bolted or otherwise fastened to the door frame B immediately below the recess or cavity 11 in the wall A, is a switch box 16, having a swinging front door 17 for access 85 thereto, and within the switch box is arranged any approved form of a swinging knife switch 18, the same being arranged in the circuit 14 and is adapted to open and close it, the knife of the switch being automatically controlled in a manner presently 90 described.

Formed on top of the box 16 is a boss 19 having a socket in which is slidably received a plunger 20, the upper portion 20' 95 of which is somewhat increased in diameter to form a shoulder 20" which by contact with the upper end of the boss 19, not only limits downward movement of the plunger but also prevents moisture that may run 100 down the plunger from passing into the socket of the boss. The plunger 20 has a reduced stem 21 which works through the top of the switch box 16 and has pivotally connected thereto, a fiber link 22, the same 105 being also pivotally connected to the knife

of the switch 18, this fiber link insulating the switch knife from the stem 21, as will be understood. Surrounding the stem 21, is an adjustable stop nut 23 which limits the 5 vertical movement of the plunger on the opening of the switch. Within the boss 19 and working against the plunger is a coiled expansion spring 24 which serves to elevate the plunger for the lifting of the knife 10 of the switch 18 to open the electric circuit to the lamp interiorly of the oven.

The plunger 20 is arranged to project in the path of movement of the weighted arm 12 so that when the door C is opened the 15 weight will strike the plunger and depress it against the resistance of the spring 24 causing the knife of the switch 18 to lower for the closing of the electric circuit 14 for illuminating the lamp on the opening of 20 the door C to the oven. When the door is closed the plunger is elevated or raised by the spring 24 and the knife of the switch 18 is lifted for the opening of the circuit 14, and thus extinguishing the lamp.

25 In Fig. 3, of the drawing, there is shown a slight modification of the invention, wherein within the box 25, which is of identical construction to the box hereinbefore described, is located a valve shell or casing 26, having mounted therein a cutoff valve 27 the operating arm 28 of which is pivotally connected to the link 29 which is pivoted to the stem 21 herein before set forth. The valve shell or casing 26 is arranged in a gas 30 supply pipe 31, which leads from a source of supply to a suitable gas jet or burner (not shown) and adapted to be located within the oven. The plunger in its modified form of the invention is active in a manner herein before set forth. Upon the gas jet or burner 35 is adapted to be arranged an automatic lighter (not shown) for the igniting of the 40

gas to illuminate the oven when the door is opened. The valve 27 is automatically opened and closed as will be apparent. 45

The lock nut 23 above referred to is provided with a set screw 23' for holding it in its different adjusted positions on the stem 21 so that the extent to which the gas flame is turned down may be adjusted and it may 50 thus be turned very low without being entirely extinguished.

From the foregoing it is thought that the construction and manner of use of the illuminator will be clearly understood and 55 therefore a more extended explanation has been omitted.

What is claimed is:

The combination with a bakers' oven of an illuminating attachment, comprising a 60 housing fixed to the door frame of the oven and having a plunger socket in its top, illuminating means arranged within the oven, a plunger slidably fitted in the socket and having a reduced stem working through the 65 top of the housing, means within the housing for turning on and off the illuminating means, a swinging door on the housing for closing the same, a coiled spring concealed 70 within the socket and active upon the plunger to normally elevate the same, a weighted arm connected with the door for movement therefrom, and disposed to engage and depress the plunger when the door is opened, and an adjustable collar on the stem of the 75 plunger to limit the elevating movement thereof.

In testimony whereof I affix my signature in the presence of two witnesses.

JOHN F. HOENNINGER, JR.
